UNITED STATES PATENT OFFICE.

PHILETUS WARREN GATES, OF CHICAGO, ILLINOIS, ASSIGNOR TO THE GATES IRON WORKS, OF SAME PLACE.

MEANS FOR LUBRICATING BEARINGS OF STONE-BREAKERS.

SPECIFICATION forming part of Letters Patent No. 551,810, dated December 10, 1895.

Application filed October 21, 1893. Serial No. 488,810. (No model.)

To all whom it may concern:

Be it known that I, PHILETUS WARREN GATES, a citizen of the United States, residing at Chicago, in the county of Cook and State of Illinois, have invented certain new and useful Improvements in Means for Lubricating Bearings of Stone-Breakers; and I do hereby declare the following to be a full, clear, and exact description of the invention, such as will enable others skilled in the art to which it appertains to make and use the same.

My invention relates to improvements in that class of rock and stone breakers in which is employed a vertical gyrating shaft carrying a crusher-head and journaled at its lower end in an eccentric-bearing, but it has more particularly to do with the peculiar construction and combination of parts whereby perfect lubrication of the said lower bearing is secured while the stone-breaker is in operation and at rest, without undue waste of the lubricating-fluid.

In the accompanying drawing forming part of this specification the figure represents a central vertical section of the devices embodying my invention.

In the accompanying drawing, A represents the gyrating shaft, which is reduced at its lower end to form a journal portion a, and this portion is loosely mounted in the eccentric-bearing B, and supported by an adjusting-step D, and a movable step-block d. This step-block is loosely seated in a recess d' formed in the supporting-chamber A', which chamber is formed integral with the bed-plate A². The adjusting-step D passes through and engages a screw-threaded passage d², and abuts against the lower end of the step-block d. Thus upon turning the step D by means of its squared end d⁴, the step-block d, and consequently the shaft A, can be raised or lowered as desired, the said step being locked in the desired position by means of the locking-nut d³. The supporting-chamber is recessed as at a', and in this recess is placed the eccentric-bearing B carrying the shaft A, but this bearing B does not fill the whole of the said recess a', but leaves at the base 50 an unoccupied portion a² which forms an oil-chamber. This chamber a² has communica-

tion with the oil supply by means of oil-passages c c. The eccentric-bearing is provided with a supporting-flange b, which rests upon a bearing-ring or washer b', which in 55 turn is mounted on the supporting-chamber A'. The bevel gear-wheel C is provided with a horizontal flange c', which fits upon and is rigidly secured to flange b of the eccentric-bearing by means of the bolts c². The gear-wheel C is also provided with an inwardly-converging flange c³, which forms an oil chamber or cup c⁴, and with obliquely-arranged radial passages c⁵ extending outward from the bottom corners of said cup to supply oil 65 to the oil-passages c c in the supporting-chamber A', the latter being provided with a circular flange e which extends upward and has its upper edge turned inward above the discharge ends of the passages c⁵, thus forming a guard to prevent the oil, issuing from the said passages, from flying over the top of said flange by reason of the centrifugal force imparted by the rotary movement of the bevel-gear. This flange also forms an 70 enlarged oil-chamber about the outer edge of the flange of the eccentric and its bearing so that said flange is fully lubricated by the oil contained therein. By the peculiar construction of the inwardly-converging flange 75 c³ any oil thrown against it is directed downward and directly into the inlets of the passages c⁵, as the points at which said passages enter said oil-chamber are located at the angle formed by side wall and bottom of said 80 chamber which is at the greatest distance from the center of rotation of the chamber. The rotary motion of the oil-chamber, with the consequent centrifugal force imparted to the oil in the chamber c⁴, is the primary 85 and principal cause of the feed of the oil to the passages c c. The oil in the chamber c⁴, when the machine is in motion, is thrown, by said centrifugal force, against the flange c³, and the consequence would be that the oil 90 would not be properly fed to the passages as ordinarily constructed and arranged and when gravity alone is relied upon to do the work; but with my construction and arrangement of the radial passages c⁵, the feed of 95 the oil from said chamber c⁴, through said passages, to the supply-passages c c is made 100

positive, and in fact has sufficient force to cause a rapid feed of all oil supplied to the chamber c^1 , while it is positively directed downward.

5 It is not necessary in some applications of my invention that the passages c extend to the bottom of the shaft and eccentric-bearing, but they, or branch passages therefrom, can be made in the supporting-chamber A' between its upper and lower ends, so as to communicate with and supply lubricant at different points along the eccentric-bearing.

The feed of the machine when at rest is by gravity alone, as there is then no centrifugal force exerted on the oil.

15 The gear C meshes with any other suitable gear connected to source of power.

The operation of the device is as follows: Oil is first supplied to the chamber c^1 , and 20 by the centrifugal force caused by the rapid rotary motion of the said chamber is forced directly through passages c^5 against flange e ; a portion of the oil insinuates itself beneath the flange b of the eccentric-bearing, and lubricates the same; and the remainder passes 25 down through the passages $c \cdot c$ or branch passages, if any are used, and fills the chamber a^2 . The bearing of the shaft A against the step-block d is thus perfectly lubricated.

30 By capillary attraction the oil is drawn up between the journal of the shaft and the eccentric-bearing, and also between the latter and the supporting-chamber A' ; and thus ef-

fectually lubricates them. The rotation of the eccentric-bearing causes the shaft A to gyrate as required.

What I claim as my invention is—

The combination with a supporting chamber provided with downward oil passages, of a flange on said chamber, an eccentric bearing and a shaft mounted in said supporting chamber, a gear wheel mounted on said eccentric bearing and turning therewith, and having an inwardly converging wall forming an oil chamber in said gear wheel; said gear wheel being also provided with radial downwardly and outwardly inclined oil passages having their inlet ends at the junction of the base and side walls of the oil chamber of said gear wheel, whereby the oil is received from the oil chamber at points therein that are the greatest distance from the center of revolution to which points the oil is thrown by centrifugal force; the construction being such that the oil discharges from the chamber under force and against the flange of the supporting chamber, and thence directly into the downward oil passages, substantially as described.

In testimony whereof I hereunto affix my 60 signature in presence of two witnesses.

PHILETUS WARREN GATES.
